UNITED STATES PATENT OFFICE

104,160

DESIGN FOR A CIGARETTE ASHTRAY

Eusebio Gordones, San Francisco, Calif.

Application March 9, 1937, Serial No. 68,089

Term of patent 7 years

To all whom it may concern:

Be it known that I, Eusebio Gordones, a citizen of the Philippine Islands, residing at the city and county of San Francisco, State of California, have invented a new, original, and ornamental Design for Cigarette Ashtrays, of which the following is a specification, reference being made to the accompanying drawing, forming a part thereof.

Fig. 1 is a top plan view of a cigarette ashtray showing my new design, it being understood that the completion thereof would involve a mere repetition of the parts shown in solid lines; and

Fig. 2 is a side elevational view, thereof.

I claim:

The ornamental design for a cigarette ashtray, as shown and described.

EUSEBIO GORDONES.
